US0D1024439S

(12) **United States Design Patent** (10) Patent No.: **US D1,024,439 S**
(45) Date of Patent: ** Apr. 23, 2024

(54) **HAIR REMOVAL DEVICE**

(71) Applicant: **Rihui Tang**, Zhejiang (CN)

(72) Inventor: **Rihui Tang**, Zhejiang (CN)

(**) Term: **15 Years**

(21) Appl. No.: **29/855,269**

(22) Filed: **Sep. 30, 2022**

(51) LOC (14) Cl. **28-03**

(52) U.S. Cl.

USPC **D28/44**

(57) **CLAIM**

The ornamental design for a hair removal device, as shown and described.

DESCRIPTION

FIG. 1 is a front and top perspective view of a hair removal device, showing my new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

1 Claim, 8 Drawing Sheets
